CLAIM

The ornamental design for a food storage box, as shown and described.

DESCRIPTION

FIG. 1 is a front, top, and left perspective view of a food storage box showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear, bottom, and right perspective view thereof; and,

FIG. 9 is a perspective view of the food storage box with the handle pulled up.

The broken lines shown in the drawings represent portions of the food storage box that form no part of the claimed design.
